UNITED STATES PATENT OFFICE

FRANK L. ROSE, OF HELENA, MONTANA

GATE

Application filed November 23, 1928. Serial No. 321,381.

The present invention is directed to improvements in gates.

The primary object of the invention is to provide a gate so constructed that a vehicle approaching the same will cause the gate to open and permit the vehicle to pass, after which the vehicle will operate means to release the gate to permit the same to swing to its closed position.

Another object of the invention is to provide a gate so constructed that an approaching vehicle will operate to elevate the gate as it swings open, means being provided to hold the gate open until the vehicle passes through the gate opening, the holding means being releasable by the vehicle to permit the gate to swing closed by gravity.

Another object of the invention is to provide a gate of this type wherein the operating mechanism is simple in construction, durable, and can be produced at a very small cost.

With these and other objects in view, this invention resides in the novel features of construction, formation, combination and arrangement of parts to be hereinafter more fully described, claimed and illustrated in the accompanying drawings, in which:—

Figure 1 is a perspective view showing the gate in its closed position.

Figure 2 is a plan view of the operating mechanism showing the pit.

Figure 3 is a fragmentary perspective view of the gate elevating means.

Figure 4 is a similar view of the gate releasing mechanism.

Figure 5 is a side view, partly in section.

Figure 6 is a sectional view through the bearing collar.

Figure 7 is a similar view, taken at right angles to Figure 6.

Figure 8 is a fragmentary top plan view of the collar.

Figure 9 is a sectional view on line 9—9 of Figure 5.

Referring to the drawings, 1 designates a main post which is embedded upon one side of the roadway and is alined with the post 2, the latter post having a latch plate 3 thereon.

A pit 4 is arranged in the roadway and is

covered by a platform 5, the walls of the pit being preferably formed from cement.

Mounted upon the platform 5 adjacent the post 1 is a collar 6 which coincides with the opening 7 formed in the platform, said collar having formed interiorly thereof diametrically opposed inclined tracks 8, the upper ends of which terminate in vertical tracks 9, the purpose of which will appear later. The gate 10 comprises tubular posts 11 and 12 which are connected by bars 13, the former post forming the pivotal mounting for the gate 10.

The post 11 has a spindle 14 carried by its upper end for rotatably engaging the bearing bracket 15 mounted upon the post 1. Fixed in the lower end of the post 11 is a plug 16 in which is mounted a transverse shaft 17 upon the ends of which are mounted rollers 18—18 adapted to engage the tracks 8 and 9 of the collar 6. The plug has an axial opening 19 in which is slidably the rod 20, said rod having its lower end extending from the lug 21 which depends from the plug 16. The post 11 has a slot 22 formed therein to slidably accommodate the curved terminal head of the rod 20.

Pivottally mounted upon the gate and engaged with the head 23 is a lever 24, to the upper end of which is pivotally connected the inner end of the latch rod 25, the forward end of which slides in the post 12 for engagement with the plate 3. The latch rod 25 has a handle 26 thereon to permit the same to be manually operated, there being a spring 27 engaged upon the rod for normally urging the rod forwardly for engagement with the plate 3.

Supported between the walls 28—28 of the pit 4 are shafts 29 and 30, which pivotally support levers 31 and 32, respectively. Between the walls 33—33 and 34—34 of the pit are mounted shafts 35 and 36 to which are pivotally connected the outer ends of the trip bars 37 and 38, respectively. The free end of the bar 37 rests upon the lever 31, while the free end of the bar 38 rests upon the lever 32, as clearly shown in Figure 3 of the drawings.

The inner ends of the levers 31 and 32 are

are arranged in overlapping relation, the overlapped portions being located under the lower end of the rod 20 in order that when the levers 31 and 32 are rocked in one direction the rod 20 will be moved upwardly to actuate the latch rod 25.

The levers 37 and 38 have carried thereby heads 39 and 40, which are arranged to normally extend above the plane of the platform 5, said platform having openings 41—41 to permit full depression of the heads when encountered by a wheel of a vehicle. These heads are capable of being removed when desired.

15 A rock shaft 42 is journaled between the walls 43—43 of the pit 4 and have arms 44 and 45 carried by its ends, said arms having heads 46 and 47 carried by their ends. This shaft is provided with a lever 48 which 20 operates between the walls 49—49 of the pit. The lever 48 has its inner end engaged with the hook 50 formed upon the lower end of the link 51, said link passing through the platform 5 and has its upper end pivoted to 25 the bar 52 which is pivotally connected to the post 53. The post 53 is placed in longitudinal alignment with the main post 1 and is spaced therefrom a distance approximately 30 the length of the gate 10. The bar 52 has carried thereby a lug 54 for engagement with the free end of the gate when in its open position.

Encircling the link 51 and interposed between the bar 52 and platform 5 is a coil 35 spring 55 which serves to normally hold the bar in a horizontal position.

End posts 56 and 57 are employed and rotatably supported by these posts as well as by the posts 1 and 53, is a rock shaft 58, 40 the outer ends of which carry arms 59 and 60, there being an intermediate arm 61 fixed to said shaft. The arm 61 is pivotally connected to the adjacent end of the bar 52 by a link 62 in order that when the shaft is 45 rocked the bar 52 will be likewise rocked. Flexibly connected to the arms 59 and 60 are hand rings 63 and 64, respectively.

The posts 56 and 57 have pivotally connected thereto levers 65 and 66, respectively, 50 said levers having flexibly connected thereto hand rings 67 and 68. The lever 65 has pivotally connected thereto the upper end of a rod 69 which passes through the platform 5 and has its lower end connected to the outer 55 end of the lever 31. A rod 70 is similarly connected to the lever 66 and has its lower end connected to the outer end of the lever 32. As shown in Figure 1 the gate 10 is in its closed position. When a vehicle approaches 60 the gate a front wheel thereof is guided upon the head 39 to depress the same, whereupon the trip bar 37 will swing downwardly thus rocking the lever 31. As the lever 31 rocks the inner end thereof will force the rod 20 65 upwardly, thus rocking the lever 24 to with-

draw the latch rod 25 from engagement with the plate 3. As the lever 31 moves upwardly it will engage the lug 21 thus forcing the post 11 upwardly, and during this upward movement the post will rotate due to the engagement of the rollers 18 in the track 8, thus 70 swinging the gate 10. As the gate continues to rotate the rollers will rise into and upwardly in the vertical tracks 9 until the lever 31 has been rocked to its fullest extent, and the 75 gate is fully opened. It will be of course understood that as the gate swings open it will also move upwardly so that the post 12 rides upon the bar 52 for contact with the lug 54. The spring 55 will hold the bar 52 yieldably 80 engaged with the gate to maintain the same open.

The gate now being open the vehicle passes through the gate opening and is guided so that a front wheel engages the head 47, which 85 rocks the shaft 42 and thus the lever 48, which pulls downwardly upon the link 51, thus rocking the bar 52, whereupon the post 12 is forced from the bar 52 by the lug 54, and the gate will close by gravity. It will be of 90 course apparent that when a vehicle approaches the gate in an opposite direction the head 40 will be encountered first to rock the lever 32 through the means of the bar 38. When the head 46 is depressed it rocks the 95 shaft 42 to release the gate to permit the same to gravitate to its closed position.

In localities where snow remains a very long period, I have found it desirable to remove the heads 39, 40, 46 and 47 and in which 100 instance the gate is opened and closed through the medium of the rings 63, 64, 67 and 68. To open the gate through the medium of the rings it will be obvious that when the ring 67 is pulled downwardly that the rod 69 will actuate the lever to elevate the gate and swing the same to its closed position, the ring 68 being actuated when it is desired to open the gate from a reverse direction. Since the rings 105 63 and 64 control the movement of the bar 52 110 110 it will be obvious that upon operating these levers the bar will be manipulated to permit the gate to gravitate to its closed position.

From the foregoing, it is thought that the 115 construction, operation and many advantages of the herein described invention will be apparent to those skilled in the art, without further description, and it will be understood that various changes in the size, shape, and proportion and minor details of construction 120 may be resorted to without departing from the spirit or sacrificing any of the advantages of the invention.

What is claimed is:—

1. The combination with a collar, of a gate 125 having a post engaged in the collar, a latch rod carried by the gate, means operable first to actuate the latch rod to release the gate and then elevate the post to swing the gate open, means for holding the gate open, and 130

means for releasing the holding means to permit the post to slide downwardly in the collar to close the gate.

2. The combination with a collar having 5 inclined tracks therein, of a gate having a post engaged in the collar, rollers carried by the post for movement in the tracks, levers operable when subjected to pressure for moving the post upward to cause the rollers to 10 travel upward in the tracks to impart rotary movement to gate to swing the same open, and means for releasing the holding means to permit the rollers to travel downwardly in the tracks to swing the gate closed.

15 3. The combination with a collar having inclined tracks therein, of a gate having a post engaged in the collar, rollers carried by the post for travel in the tracks, levers mounted in the roadway and operable by 20 pressure for engagement with the post to elevate the same to cause the rollers to travel in the track to swing the gate to its open position, means for holding the post in its elevated position, and means for releasing the holding 25 means to permit the rollers to travel downwardly in the tracks to swing the gate closed.

4. The combination with a collar, of a 30 gate having a post rotatably engaged in the collar, pivotally mounted levers operable to move the post upwardly to impart rotary movement thereto to open the gate, means for holding the gate open, and means for releasing the holding means to permit the post to move downwardly in the collar to close 35 the gate.

5. The combination with a collar, of a 40 gate having a post rotatably engaged in the collar, a latch rod carried by the gate, a rod slidable in the post, levers, means for operating the levers to slide the second named rod to release the latch bar said levers serving to elevate the gate in the collar, and means for rotating the post during elevation thereof to swing the gate to open position.

45 6. The combination with a collar, of a gate having a post rotatably engaged in the collar, pivotally mounted levers associated with the post, heads connected with the levers, said heads when subjected to pressure 50 serving to rock the levers to move the post upwardly in the collar, cooperative means carried by the collar and post for imparting rotary movement to the post during elevation thereof to swing the gate open.

55 In testimony whereof I affix my signature.
FRANK L. ROSE. [L. S.]
